(57) **CLAIM**

The ornamental design for an entertainment device remote control, as shown and described.

DESCRIPTION

FIG. 1 is a perspective view of the top of entertainment device remote control showing our new design;

FIG. 2 is a top view thereof;

FIG. 3 is a left side view thereof;

FIG. 4 is a bottom view thereof; and,

FIG. 5 is a perspective view of the bottom of entertainment device remote control.

In the drawings, the broken-line buttons depict environmental subject matter only and form no part of the claimed design.
